CLAIM

The ornamental design for a syringe barrel with needle as shown and described.

DESCRIPTION

FIG. 1 is a perspective view of a syringe barrel with needle, showing my new design;

FIG. 2 is a front view thereof, a rear view being a mirror image to the front view;

FIG. 3 is a top plan view thereof;

FIG. 4 is a bottom plan view thereof;

FIG. 5 is a left side view thereof;

FIG. 6 is a right side view thereof;

FIG. 7 is a cross-sectional view thereof taking along line 7-7 in FIG. 5;

FIG. 8 is a cross-sectional view thereof taking along line 8-8 in FIG. 5; and,

FIG. 9 is an enlarged perspective view of the detail identified in rectangle 9 in FIG. 1.

The dashed lines depict portions of the syringe barrel with needle that form no part of the claimed design. The dot-dashed lines depict the boundaries of the claim and form no part thereof. The oblique line shadings indicate the transparent portion.
